UNITED STATES PATENT OFFICE

EDWIN B. STIMPSON, OF BROOKLYN, NEW YORK, ASSIGNOR TO EDWIN B. STIMPSON COMPANY, OF BROOKLYN, NEW YORK, A CORPORATION OF NEW YORK

RIVETING MACHINE

Original application filed February 25, 1928, Serial No. 257,011. Divided and this application filed November 10, 1928. Serial No. 318,516.

This invention relates to rivet setting machines and has for its object to increase the field of work to which such machines are adapted and also to increase the facility of 5 operation for such machines, especially with large work.

Rivet feeding and setting machines have been found to be desirable in the construction of a great variety of articles. Efforts have 10 been and are being made to increase the field of utility for these machines. Heretofore large hollow and cumbersome articles were not readily adapted for construction by such machines except in the early stages and before those articles were formed. With this 15 invention these disadvantages are overcome.

According to this invention the usual rivet setting mechanism is provided but the anvil support is constructed to provide greater 20 clearance below the anvil and toward the rivet setting mechanism support, said clearance also extending below the anvil on at least three sides thereof.

This application is a division of my prior 25 application Serial No. 257,011, filed February 25, 1928; and in distinction from the embodiment specifically claimed therein, a particular object of the present application, as hereafter claimed, is to provide greater 30 clearance, or space, for the "work" and also for the operator, in front of, and at one side of the machine, than is available in the specific form shown in the parent application.

Referring to the drawing, Fig. 1 is a front 35 elevation of one embodiment of this invention.

Fig. 2 is a view partly in plan and partly in section, on the line 2—2, Fig. 1.

As shown in Fig. 1, the base 10 supports the usual standard 11 surmounted by the customary head 12 to which is attached an ordinary rivet feeding mechanism 13 and rivet setting mechanism 14. The customary anvil 15 is provided for cooperation with said rivet setting mechanism 14.

An extension 16 is provided on the base 10 and has finished vertical surfaces to which the anvil standard 17 is secured by bolts 18 or otherwise as desired. The standard 17 is illustrated in Fig. 1 as diverging upwardly 45 away from the standard 11 so as to increase

the clearance below the anvil 15 and between the two standards 11 and 17. A laterally extending arm 19 supports the anvil 15 from the upper portion of the standard 17, said arm being secured to the standard by means of 55 bolts 20, or by other suitable securing means. The standard 17 is preferably a casting while the arm 19 should be of steel to avoid fracture and provide the requisite strength for rigidly supporting the anvil.

The machine illustrated is adapted for work upon large articles like bags, suitcases, trunks, barrels, large containers of various shapes which could not be conveniently handled by prior rivet setting machines. While the machine illustrated is provided with a stationary anvil, the desired large clearance may be similarly provided with other types of rivet setting machines, such for example as those having reciprocating or 70 rotary anvils designed for particular purposes. This machine is adapted for use with various types of rivets and it will be understood that the anvil may be shaped to accord with the particular type of rivet used, for example, whether split or solid or tubular. The usually actuating treadle 21 for the rivet setting mechanism is located sufficiently low and close to the base as not to interfere with the desired clearance below the anvil 15, nor is the 75 usual spring 22 for returning the treadle 21 in the way, as it is located quite close to the standard 11.

In distinction from the parent application, above referred to, of which the present is a 85 division, the base extension 16 projects to the operator's left side and slightly to the rear. The standard 17 diverges upwardly and rearwardly, away from standard 11 and operator's position, while arm 19 extends forwardly as well as laterally, providing greater clearance at the front and left side of the machine.

I claim:

1. The combination with a rivet setting 95 mechanism, of an anvil for cooperation therewith, a standard supporting said mechanism, another standard on one side of the first standard with respect to the operator's position, a member supporting said anvil from 100

said second mentioned standard, said second mentioned standard being located somewhat behind and farther from the operator's position than said first mentioned standard.

5 2. The combination with a rivet setting mechanism, of an anvil for cooperation therewith, a standard supporting said mechanism, another standard on one side of the first standard with respect to the operator's position, a member supporting said anvil from said second mentioned standard, said second mentioned standard being located somewhat behind and farther from the operator's position than said first mentioned standard, and
10 15 said anvil supporting member extending laterally and forwardly from said second mentioned standard.

3. The combination with a rivet setting mechanism, of an anvil for cooperation therewith, a standard supporting said mechanism, another standard on one side of the first standard with respect to the operator's position, a member supporting said anvil from said second mentioned standard, said second mentioned standard being located somewhat behind and farther from the operator's position than said first mentioned standard, and slanting generally rearwardly and laterally divergently therefrom.

20 4. The combination with a rivet setting mechanism, of an anvil for cooperation therewith, a standard supporting said mechanism, another standard on one side of the first standard with respect to the operator's position, a member supporting said anvil from said second mentioned standard, said second mentioned standard being located somewhat behind and farther from the operator's position than said first mentioned standard, and inclined laterally and rearwardly therefrom, and said anvil supporting member extending laterally and forwardly from said second mentioned standard.

25 In testimony whereof I affix my signature.
EDWIN B. STIMPSON.
